UNITED STATES PATENT OFFICE.

HERMAN MECKING, OF NEW YORK, N. Y.

ASH-CAN.

1,249,983.

Specification of Letters Patent. Patented Dec. 11, 1917.

Application filed May 11, 1917. Serial No. 167,916.

To all whom it may concern:

Be it known that I, HERMAN MECKING, a citizen of the United States, and being a resident of the city of New York, borough 5 of Bronx, in the county of Bronx and State of New York, have invented a new and Improved Ash-Can, of which the following is a full, clear, and exact description.

My invention relates to ash cans provided 10 with a cover.

An object thereof is to provide a simple, strong, inexpensive and sanitary ash can which has a sectional cover adapted to prevent the discharge of the contents unless the 15 can is subjected to a shock whereby the contents throw the cover open and are free to discharge.

With the above and other objects in view, the nature of which will more fully appear 20 as the description proceeds, the invention consists in the novel construction, combination and arrangement of parts as herein fully described, illustrated and claimed.

In the accompanying drawings, forming 25 part of the application, similar characters of reference indicate corresponding parts in all the views.

Figure 1 is a top plan of my can, certain 30 parts of which are broken away to show the details of construction;

Fig. 2 is an elevation of the can in inverted position, partly in section on line 2—2, Fig. 1, the can being shown at the moment when it receives an impact which 35 throws the sectional cover open under the momentum of the contents;

Fig. 3 is a fragmentary vertical section on line 3—3, Fig. 1; and

Fig. 4 is an elevation of the can with the 40 cover up.

Referring to the drawings, the can 5 is preferably frustocone shape, the larger diameter being at the top. At the top edge it is preferably reinforced by the formation 45 of a bead 6 on the exterior surface of the can. It has also at the top an interior rim 7, the upper edge of which is slightly depressed from the top edge of the can. On this edge the sections 8 of the cover rest when they are 50 closing the can. Each of the sections 8 is hinged to the can at the top, the stationary part 9 of the hinge being secured to the inner surface of the can. It is preferably tapered to prevent obstruction to the movement of 55 the contents outwardly.

The cover sections 8 are locked in the

closed position by members 10 and 11, the member 10 forming a projection which extends over the proximate edge of the adjacent cover section 8 when the two sections 60 are in closed position, and the member 11, which is secured to the other section, yieldingly gripping the projection 10. The member 11 begins to engage the projection 10 before the two covers reach the closed position. When they are in closed position there is a firm grip of the member 11 on the projection 10; and the resiliency of the member 11 is such that the weight of the contents of the ash can, even if moist, is not sufficient 65 of itself to force the cover sections open; but the slightest shock to the can gives a momentum to the mass forming the contents, which swings the sectional cover 8 outwardly and allows the contents to discharge. 70 The momentum results from an obstruction 13 interposed to the bead 6 when the can is in an inverted position (see Fig. 2).

To facilitate the manipulation of the can, it is provided with a reinforcing belt 12 80 having loops 13 at right angles to each other, which constitute the handles of the can. These handles also permit the manipulation of the can by mechanical means on specially constructed wagons which are used in some 85 communities.

The hinges of the cover sections being located slightly below the upper edge of the can allows the covers to lean slightly against the edge when they are thrown open and 90 thereby facilitates the loading of the can without the use of any retaining means for the covers. (See Fig. 4).

I claim:

1. An ash can having cover sections each 95 hinged at the inner side near the top of the can, a projection on one of said cover sections adapted to extend over the other when the sections close the can, and a yielding member on the other section for engaging 100 the projection when the cover is in closed position, said yielding member adapted to prevent the parting of the cover sections under the weight of the contents in the can, but adapted to yield under an impact to the 105 cover by the contents, whereby the cover sections are free to swing outwardly.

2. An ash can having an outward bead at the top thereof, semicircular cover sections hinged on the inner side of the can below the 110 bead so that said cover sections will lean against the bead when thrown into open po-

sition, a projection on one of said cover sections adapted to project over the other section when the sections are in closed position, a resilient member on the other section for engaging the projection when the sections are moved into the closing position, an interior rim forming a rest for the sections in closed position, said resilient member

adapted to retain the sections in closed position under the weight of the contents in the can but adapted to release the projection when the contents receive an impact, and a reinforcing belt on the can having loops at right angles thereto constituting handles for the can.

HERMAN MECKING.
